PASTE DISPENSER

Carl F. Geyer, deceased, late of Charlotte, N. C.,
by Eula Pierce, administratrix, Charlotte, N. C.,
assignor to Catherine M. Geyer

Application November 19, 1945, Serial No. 629,420

1 Claim. (Cl. 222—102)

1

This invention relates to a dispensing apparatus and more especially to an apparatus of this type which is adapted to be associated with a collapsible tube containing tooth paste and the like.

It is an object of this invention to provide a simple and efficient dispensing mechanism which has means associated therewith for squeezing a collapsible tube containing paste and forcing desired quantities onto a brush or other article upon which the paste is adapted to be used.

It is a further object of this invention to provide a dispensing apparatus of the class described comprising a collapsible tube with means for resiliently pressing said tube to force the paste therein, from the same, and means for automatically opening the port of said tube upon the operation of the squeezing mechanism. Also means are provided whereby the port of the tube will be automatically closed when the operation of the squeezing mechanism ceases.

Some of the objects of the invention having been stated, other objects will appear as the description proceeds when taken in connection with the accompanying drawings, in which—

Figure 1 is a top plan view of a form of the invention with the top cover removed;

Figure 2 is a longitudinal sectional view taken along the line 2—2 in Figure 1 and showing the cover in place and showing the top piece of spring steel broken away;

Figure 3 is a view partly in section and taken along the line 3—3 in Figure 1;

Figure 4 is a view taken along the line 4—4 in Figure 1 and showing the cover plate removed;

Figure 5 is a sectional view taken along the line 5—5 in Figure 3 and showing the stop pinion 112 also;

Figure 6 is a view of the discharge end of the apparatus showing the closure in closed position;

Figure 7 is a view similar to Figure 6 but showing the parts in position to open the discharge port;

Figure 8 is a view similar to Figure 6 but showing the cover in position and a portion thereof broken away;

Figure 9 is a view looking at the left-hand side of Figure 8 but omitting the handle and operating mechanism and showing a portion of the cover broken away;

Figure 10 is a top plan view of the upper left hand portion of Figure 8 but showing the handle and operating mechanism removed;

Figure 11 is a view looking at the left hand side of Figure 8 and showing the cover disk removed and showing the parts in fully advanced position and omitting the sliding closure gate;

Figure 12 is a sectional view taken along the line 12—12 in Figure 11.

2

Referring more specifically to the drawings, the numeral 75 indicates a casing while 76 indicates a suitable cover which is snapped in position by means of a spring dog 77 disposed on the rear end wall of the casing 75 and engaging a suitable cavity on the interior surface of cover 76. The casing 75 has a block 78 secured therein on which is secured the rear end of a piece of spring steel 79. The front end wall of the casing 75 has a cavity 80 therein in which the screw-threaded neck 81 of a tube of paste 82 is adapted to fit.

The discharge end of cavity 80 is closed by a metallic plate 88 having overhanging lips 83 and 84 in which a gate member 85 is slidably mounted. The gate member has an opening 86 therein adapted at times to coincide with an opening 87 in plate 88 and communicating with the cavity 80 and into which the screw-threaded neck of the tube 82 is adapted to fit. The bottom of the casing 75 has secured therein a metallic plate 89 to which the member 78 is attached.

Rising upwardly from the rear end of the casing 75 is a pair of projections 90 and 91 which have sprocket wheels 92 and 93 rotatably mounted on the proximate sides thereof on suitable screws 94 on which sprocket chains 95 and 96 are mounted. A U-shaped member 97 is adapted to slide on the plate 89 and it has a pair of rollers 98 and 99 rotatably mounted therein and adapted to engage the spring steel plate 79. Adapted to rest on top of the tube 82 is a second spring steel member 100 provided with an upturned rear portion 101. Adapted to rest on the spring steel member 100 is a roller 102 rotatably mounted on a shaft 103 fixedly secured in outstanding lugs 104 appearing on each of the vertical legs of the U-shaped member 97.

Suitable screws 105 penetrate the lower layers of the sprocket chains 95 and 96 and are threadably received in lugs 104 to thereby cause the lower layer of the sprocket chains 95 and 96 to move the U-shaped member along with rollers 98, 99, and 102 to the left in Figures 1 and 2 to press the spring steel members 79 and 100 towards each other to force paste from the tube 82.

50 The plate member 88 having the opening 87 therein and having the outwardly and inwardly turned lip portions 83 and 84 forms a guideway in which closure member 85 is slidably mounted. This closure member has an uprising projection 105 which is engaged by a cam 106 on a cylindrical member 107, the interior structure of which will be presently described.

55 The front end wall of the casing 75 has a projection 108 extending thereacross and rising upwardly therefrom in which is rotatably

mounted a shaft 109. This shaft 109 has fixedly secured thereon sprocket wheels 110 and 111 on which the sprocket chains 96 and 95, respectively, are mounted. The shaft also has fixedly secured thereon a gear or pinion 112 which is engaged by a spring detent 113 having one end thereof secured in the cover portion 76. This holds the parts in the position to which they are moved and prevents retrograde movement.

The cylindrical member 107 has a hub portion 115 integral therewith which is rotatably mounted on shaft 109. The cylindrical portion 107 has an inwardly projecting portion 116 which is also rotatably mounted on shaft 109.

Loosely mounted around the hub portion of member 115 is a torsion spring 118 which is hooked around a pin 120 projecting from one side of the casing member 75 and the other leg of the spring 118 is anchored to a portion 117 which is integral with the cylindrical member 107. The cylindrical member 107 has a handle portion 135 extending therefrom so that when the cylindrical member is given a part rotation, the torsion spring 118 will return it to the position shown in Figures 1, 2, and 6. Secured on the end of shaft 109 by means of a screw 121 is a ratchet wheel 122 which is also keyed on the shaft 109 by means of a keyway 123. The screw 121 also penetrates a cover plate 124 to cover the outer side of the cylindrical member 107.

Pivotedly mounted on the inside of the cylindrical member and to the portion 115 as by means of a screw 126 is a pawl member 127 having a tooth 128 thereon. The tip of pawl 127 is slidably mounted behind a pin 129 and is pressed towards the ratchet wheel 122 by means of a leaf spring 130 having one end welded or soldered to the pawl 127. The inner surface of this pawl 127 is adapted to ride on the free end of pin 129 as the tooth 128 does not extend all the way across the inner surface of the pawl 127, thus, allowing the pin 129 to pass by the tooth 128.

Method of operation

With the parts in the position shown in Figures 1, 2, 6, and 8, and with the cover in position as shown in Figure 2, the handle 135 is moved in a clockwise manner in Figure 2 to the position shown in Figure 11. As movement is first imparted to the handle, the cam 106 on cylindrical member 107 proceeds to open the gate 85 to where openings 86 and 87 will coincide; and, when this point has been reached, pin 126 will occupy a position as shown in Figure 11, pin 128 being fixed to the lower casing 75. At this point, the radial distance of pin 129 from the pivot point 126 of pawl 127 will allow the tooth 128 to engage the ratchet wheel 122 which will then begin to rotate shaft 109 which will advance roller 102 to squeeze a small amount of paste from the tube. When the handle 135 is released, the spring 118 will move the parts back to normal position as shown in Figures 1 and 2.

When the paste in tube 82 is exhausted, the cover can be removed, which will release detent 113 from wheel 112, making the shaft 109 freely rotatable and the chains can be seized and reversed to place the roller 102 back at the extreme right hand side of Figures 1 and 2 against upturned portion 104 of spring steel plate 100 and a new tube can be inserted and the cover again

placed in position and the dispenser will be ready for operation.

If desired, the base of cover 75 may have one or more suitable bayonet slots having an enlarged portion 136 and a restricted portion 137 which can be slid over and moved downwardly over a suitable pin, not shown, in a wall which will hold the dispenser in position.

In the drawings and specification there has been set forth a preferred embodiment of the invention, and although specific terms are employed, they are used in a generic and descriptive sense only, and not for purposes of limitation, the scope of the invention being defined in the claim.

What is claimed is:

Apparatus for dispensing paste from a tube comprising a casing having means for receiving a tube of paste, the front end of the casing having a cavity therein for reception of the open end of the tube, the front end of the casing having an opening extending from the cavity to the exterior of the casing, a sliding closure for the opening, a spring steel plate having its rear end mounted in the rear end of the casing in spaced relation from the bottom of the casing and on which a tube of paste is adapted to rest, a second spring steel member adapted to rest on top of the tube, a U-shaped member having a lower roller adapted to travel along the lower surface of the first spring steel member and having an upper roller adapted to travel along the top surface of the second spring steel member, to thereby compress the tube disposed between the two spring steel members, a pair of endless chains mounted at each end of the casing for rotation and having their lower portions secured to the U-shaped member, the mounting of the chains at the front end of the casing comprising a transversely disposed shaft rotatably mounted in the casing and having a pair of sprocket wheels thereon on which the chains are mounted, a ratchet wheel fixed on one end of the shaft, oscillatable means on said shaft having a dog for engaging the ratchet wheel after the oscillatable means have been moved a predetermined amount for imparting rotation to the shaft and a connection between the oscillatable means and the closure means for moving the closure from over said opening before rotation is imparted to the shaft.

EULA PIERCE,
Administratrix of the Estate of Carl F. Geyer,
Deceased.
